SHOCK PROOFING MOUNTING MEANS FOR VACUUM TUBES

Filed Nov. 8, 1924

UNITED STATES PATENT OFFICE.

LAWRENCE C. F. HORLE, OF NEWARK, NEW JERSEY, AND NICHOLAS HEYMAN, OF BUFFALO, NEW YORK, ASSIGNEES TO FEDERAL TELEPHONE MANUFACTURING CORPORATION, OF BUFFALO, NEW YORK, A CORPORATION OF NEW YORK.

SHOCK-PROOFING-MOUNTING MEANS FOR VACUUM TUBES.

Application filed November 8, 1924. Serial No. 748,620.

To all whom it may concern:

Be it known that we, LAWRENCE C. F. HORLE and NICHOLAS HEYMAN, citizens of the United States, residing at Newark, in the county of Essex and State of New Jersey, and at Buffalo, in the county of Erie and State of New York, respectively, have invented certain new and useful Improvements in Shock-Proofing-Mounting Means for Vacuum Tubes, of which the following is a specification.

The invention relates to mounting means for vacuum tubes or similar devices, and more particularly to shock-proofing mounting means for a tube or tubes mounted upon a unit which forms part of a radio receiver.

As is well known, microphonic noises are likely to cause trouble in radio receivers or other apparatus in which vacuum tubes are used, due to shock or vibration transmitted to the tube electrodes from outside sources. To avoid this trouble various systems of shock absorbing for the tubes have been proposed, and it is the general object of this invention to provide an improved system of this character.

A further object is the provision of shock proofing resilient means, in combination with mounting means for the tubes, of such construction that the tubes and related parts supported by the resilient means may be readily removed or replaced as a unit.

Another object is to provide a shock proofing system which comprises resilient supporting means of extreme sensitiveness but which at the same time is not likely to lose its effectiveness or to cause damage to tubes or other parts when the receiver or other apparatus in which it is used is subjected to rough handling.

Another object is to provide a simple and efficient damping means for the resilient means which form part of the shock proofing system.

To accomplish the above objects and other objects which will appear in the description which follows, the tubes are mounted on a tube shelf to which are also secured amplifier and other elements of the receiver, and the shelf with its attached parts is enclosed in a can or casing forming a continuous metal

shield. The tube supporting member thus formed, and carrying the tubes, is of considerable mass, and this heavy unit is suspended by damped helical springs on a frame or other supporting body portion of the receiver. The connection means for the helical springs by which the unit is suspended are so arranged that the unit, comprising the can and its contained and attached elements, may readily be removed from or replaced in the receiver.

Supplementing the shock proofing means, stop means are preferably provided comprising elements of resilient or fibrous or other suitable material, interposed between the floating unit and the frame or other fixed members of the receiver to prevent too great movement of the unit within the receiver at any time, but which allow the unit to remain freely suspended when in normal use.

Referring to the drawings:

Figures 1, 2 and 3 are respectively a side elevation, a plan view and an end elevation of an embodiment of tube mounting and shock proofing means in accordance with the invention.

Figure 4 is a detail view of a pair of shock proofing springs and a connection means for the springs to a frame member.

Figure 5 is an enlarged view of a shock proofing spring showing damping means for the spring.

In Figs. 1, 2 and 3, a frame 1 is mounted in any suitable manner on a supporting member as 2, which may be the base of a cabinet or casing for radio apparatus such as a receiver. A tube shelf 3 carries tubes 4 which are mounted in the sockets 5. Secured to the tube shelf are other operating parts of the receiver, as transformers 6 which may be of the A. F. type, transformers 7, which may be of the R. F. type, grid leak 8 and condenser 9. The parts are preferably those, in any given apparatus, which, with the tubes, may form a convenient operating unit properly interconnected as to its several parts and with wires as 10 which serve to make connection to other outside parts such as tuning devices and batteries. The parts are preferably arranged in such a manner on the tube shelf that the assembly is ap-

proximately balanced about its center, as, for example, by mounting the heavy iron core A. F. transformers 6 directly under the shelf and at its extreme ends, with other 5 lighter parts such as R. F. transformers 7 between. A metal casing or can 11 encloses the tube shelf and all attached parts except the tubes. The can comprises a cover member 12 secured to the tube shelf and a body 10 member 13 fastened to the cover.

The entire unit comprising the tube shelf carrying the tubes, and with transformers and other related parts enclosed by the can which forms a shield, is suspended on frame 15 1 by a number of helical springs 14. Eight of such springs may be used disposed at or near the ends of the can. The springs are preferably so placed with reference to the can and the frame that certain of them, for 20 example the upper four, extend diagonally outwardly and upwardly from the can to the frame, and others, as the lower four, extend diagonally outwardly and downwardly from can to frame. In order to simplify 25 manufacture, assembly and replacement the springs are preferably arranged in pairs near the upper corners of the can. The springs of each pair are hooked to lugs 15 formed in the cover member 12. The outer 30 ends of each pair of springs are hooked to a spring suspension member as spring bracket 16, the two spring ends being set at points comparatively far apart on the spring bracket, as in holes 17 formed near 35 the ends. The springs of each pair extend diagonally outward from a lug, one of the springs extending diagonally upwardly to the bracket and the other downwardly. The bracket is formed in such a manner as to be 40 readily set or slipped upon a frame member 18, or other fixed supporting member, and to be held in position thereon by the tension of the springs and preferably not secured by any other means.

45 The preferred construction of the spring mounting means which comprise the spring brackets 16 will be better understood by reference to Fig. 4, which is a detail perspective view of a spring bracket in place on an up-right frame member 18, shown for clearness as broken away immediately above the bracket. As shown in this figure, the plate of which the bracket is formed is bent at the edge opposite the springs to 50 form a portion 19 which abuts against the edge of frame member 18, and which is extended partially around the edge in order to hold the bracket firmly hooked to the frame. The bracket is located on the 55 frame member and held from slipping longitudinally by a lug 20 lying within a recess 21. The lug 20 and recess 21 are formed preferably in frame member 18 and bracket 16 respectively. When the unit is in position in the receiver the four spring brackets

are drawn tightly against the frame members by the springs, and held in this position without special fastening means, and the unit itself is freely suspended from the brackets. In order to remove the unit from 70 the frame it is only necessary to draw the brackets back from the frame enough to release them and to allow them to hang free on their springs. It is evident that in replacing the unit, the brackets are simply 75 snapped over the frame members into position. It is to be further noted that in the initial assembly of the shock proofing system, the entire spring suspension apparatus is first assembled on the can, outside the receiver, with the springs attached to the brackets ready for the easy placing, within 80 the receiver, of the unit which carries the tubes.

Stop means comprising blocks as 22 of felt, 85 rubber or other soft or resilient material are preferably provided. These may be located at suitable points on the frame or other supporting members of the receiver, and so placed and dimensioned, for example, as to bear against the bottom or sides of the body portion 13 of the can which encloses the suspended unit in case the unit is forced from any cause more than a predetermined 90 amount from its normal operating position. 95

Damping of the helical springs is accomplished preferably as indicated in Fig. 5 by a damping member 23, which may be of felt, cotton batting or other similar fibrous or soft material stuffed or forced into the 100 spring and bearing against the turns.

It will be seen that in the shock proofing system herein described a high degree of efficiency is obtained due to the combination with small suspension springs, which form a very loose mechanical coupling between unit and frame and permit free relative movement of the frame with reference to the unit in any direction whatever, of the evenly balanced and comparatively large mass of the unit which carries the tubes. The heavy unit, with its sluggish response to movement or vibration which can only come through the sensitive and resilient springs, virtually floats in its suspension system within the frame. Further, the damping means for the springs deaden vibration of the spring structure itself before the vibration reaches the unit. The total effect of the combination of the heavily 110 loaded unit carrying the tubes, the sensitive spring suspension and the thoroughly damped springs is the effectual stoppage or absorption of shocks and vibrations, transmitted in any direction through the receiver before they can reach the tube electrodes. 115

120 It will be seen further that the spring suspension arrangement, which, together with the loaded unit which carries the tubes, 125 is comprised in the shock proofing system,

permits the ready removal and replacement of this complete operating unit for testing or repair purposes.

What is claimed is:

5 1. In a shockproofing mounting system for a vacuum tube, a supporting frame, a base carrying the tube, and eight helical extension springs for resiliently connecting said base to said frame, one set of four of
10 said springs extending diagonally outwardly and upwardly from base to frame, two of said set of four springs being connected respectively at opposite points on the sides of said base and near one end thereof, the
15 other two of said set of four springs being connected respectively at opposite points on the sides of the base and near the other end thereof, a second set of four of said eight
20 springs extending diagonally outwardly and downwardly from base to frame, two of said second set of four springs being connected respectively at opposite sides of said

base and near one end thereof, the other two of said second set of four springs being connected respectively at opposite sides of said 25 base and near the other end thereof.

2. In a shock proofing mounting system for a vacuum tube, a supporting frame, a rectangular base carrying the tube, a comparatively large mass rigidly secured to said 30 base, and eight helical extension springs connected between base and frame for resiliently suspending and confining said base, with attached mass and tube, within said frame, said springs being attached to said base near 35 the corners thereof, four of said springs extending diagonally outwardly and upwardly from base to frame, the other four of said springs extending diagonally outwardly and downwardly from base to frame. 40

In witness whereof, we hereunto subscribe our names.

NICHOLAS HEYMAN.
LAWRENCE C. F. HORLE.
